DESIGN FOR A HAT OR SIMILAR ARTICLE

Irving H. Ross, Hunter, N. Y., assignor to Glens-der Textile Co., New York, N. Y., a firm composed of Edwin Rosenberg, Louis Grossman,
Arthur Klein, and Sidney Nathan

Application October 2, 1941, Serial No. 103,613

Term of patent 3½ years

To all whom it may concern:

Be it known that I, Irving H. Ross, a citizen of the United States of America and residing at Hunter, in the county of Greene, State of New York, have invented a new, original, and ornamental Design for a Hat or Similar Article, of which the following is a specification, reference being had to the accompanying drawing, forming part thereof.

I claim:

The ornamental design for a hat or similar article, as shown and described.

IRVING H. ROSS.
